UNITED STATES PATENT OFFICE.

WILLIAM OGLESBY PASSMORE, OF LIVERPOOL, ENGLAND, ASSIGNOR, BY MESNE ASSIGNMENTS, TO AUTOMATIC ELECTRIC INC., OF CHICAGO, ILLINOIS, A CORPORATION OF DELAWARE.

SEMITAUTOMATIC TELEPHONE SYSTEM.

Application filed November 25, 1924, Serial No. 752,138, and in Great Britain November 30, 1923. Renewed November 6, 1928.

The present invention relates to semi-automatic telephone systems and more particularly to systems in which calls may have to be completed either to automatic or manual subscribers. The invention will be described in detail in connection with an arrangement whereby calls are set up from a manual exchange but it should be understood that many of the features of the invention are applicable to cases in which automatic subscribers originate calls which are then completed by means of register translators.

Calls which are extended over automatic numerical switches to manual exchanges will generally be dealt with at call indicator positions where the wanted number is displayed to the operator by means of lamps or other indicators. It has already been proposed, as described in the co-pending application of Ostline, Serial No. 630,726, filed April 9, 1923, issued Aug. 14, 1928 as Patent 1,680,565, to transmit the wanted number over the trunk line not by means of impulses such as are used for operating stepping switches but in a special code whereby the transmission time may be appreciably reduced.

It is one object of the present invention to provide an impulse sender which will send ordinary impulses to operate the switches for selecting the exchange and then according as an automatic or a manual exchange has been selected will transmit the numerical portion of the wanted number in ordinary impulses or in a special code for operating a call indicator. Ordinary impulses or circuit interruptions such as are used for operating step-by-step switches will for the sake of convenience be termed hereafter stepping impulses. The arrangement whereby the trunk lines outgoing from an operator's position lead to automatic switches having access to both manual and automatic exchanges presents the advantage that the code sending device and the storage devices for recording the wanted subscriber's number may be provided in groups common to all or to a large number of the call indicator exchanges in a network.

According to one feature of the invention an impulse sender is provided comprising register sets on which wanted subscribers' numbers are stored and sending devices of two different kinds associated with the regis-

ter sets, one for sending impulses to operate the switches which perform an exchange selecting function and the other for sending impulses in a code suitable for operating call indicators at the exchange selected.

According to another feature of the invention in an impulse sender comprising register sets and two different kinds of sending devices, means are provided whereby one sending device transmits impulses of one kind corresponding to a portion of the required number and the other sending device subsequently transmits impulses of a different kind corresponding to another portion of the required number. Determining means are also provided whereby either one sending device or the other is brought into operation depending upon the destination of the call.

A further feature of the invention is the provision of an impulse sender comprising a register set on which wanted subscriber's numbers are adapted to be set up and sending devices of two kinds controlled by the register set, that part of the register set which registers the exchange designation of the wanted subscriber being adapted to cause the operation of one sending device to control switches for selecting the required exchange and also to determine whether subsequently the first device will continue to operate or the second device be brought into operation to transmit impulses of a different kind in accordance with the setting of the other part of the register set which registers the numerical designation of the wanted subscriber.

Still another feature is that where connections are set up over automatic switches with the help of operators by means of keyboard controlled impulse senders common to a large group of operators, the same impulse senders may be used for setting up connections to both automatic and manual exchanges.

Other features relate to the delaying of the sending of code impulses until the call indicator operator is ready to receive them, to the use of trunk finders for connecting an outgoing trunk with an impulse sending device to a device for compensating the code sending circuit for different lengths of trunk line and to various advantageous smaller provisions for improving the operation of the impulse sender and facilitating the establishment of calls.

These features will be better understood from the following detailed description of the operation of one embodiment of the invention, though, as mentioned above, it may be applied 5 in other circumstances than those shown and obviously detail modifications may be made without exceeding the scope of the invention.

In the accompanying drawings, Fig. 1 shows the general layout of the system described, and Fig. 2 shows a trunk finder and the apparatus associated with an outgoing trunk line. Fig. 3 shows the operator's key set, the outlet finder and a sender selector; Fig. 4, indicates the input control switch and the 10 sender controlling relays, while Fig. 5 shows the storage relays, code switch and intermediate distributing frame. Fig. 6 illustrates the output control switch, and two different sender switches and the compensating arrangements. It will be understood that Figs. 2-6 are to be placed together with the corresponding lines in alignment in order to form the complete system as diagrammatically shown in Fig. 1.

The general layout of the system, Fig. 1, in many respects closely resembles that shown in the co-pending application of Gillings, Serial No. 723,124, filed June 30, 1924, but differs in several important points, this layout 25 will first be briefly described. The operator, at the position O at the originating manual exchange will be signalled in the usual manner by a calling subscriber and on learning his requirements, will repeat the wanted subscriber's number to the tandem operator over an order wire (not shown). The tandem operator will thereupon give her the number of an idle interexchange junction line, at the same time pressing the assignment key A associated with this line. In the drawing, Fig. 30 1, only one such junction line is shown.

In response to the pressure of the assignment key, a circuit is completed over the outlet finder OF, and back contact and armature G' in the preselected outlet for the sender selector SS¹ which thereupon commences hunting for a free sender. At the same time the trunk finder TF¹ associated with this outlet is started up to find the line in connection 45 with which the assignment key has been pressed. When these switches find an idle sender and the assigned trunk line respectively, the operator is notified by the lighting of a lamp and she may then set up the required 50 number by operating the appropriate keys of her key set K.

In response to the operation of the first key, a circuit is completed over the outlet finder OF in the position shown, back contact and 55 armature G¹, sender selector SS¹, armature W¹ and its back contact, over the wipers of the input control switch ICS in first position to the first set of storage relays all of which are represented in Fig. 1 by the rectangle 60 SR. The switch ICS is moved on one step as

each key is released, and in consequence a different set of storage relays is operated each time a key is pressed. When three digits have been registered, a circuit is completed for starting up the code switch CS which 70 then hunts to find contacts which have been marked by the operation of the first three sets of storage relays. In the meantime the operator will be setting up the remainder of the number which in the case described will comprise four numerical digits. 75

It will be assumed in the present instance, that the call is going to a call indicator exchange, and hence the exchange selecting digits, after being translated as will be more 80 fully described subsequently, are transmitted in the form of impulses for operating step-by-step switches of the ordinary type, while the four digits corresponding to the actual subscriber's number are subsequently sent out 85 over the trunk line in code whereby a considerable saving of transmission time may be effected.

When all the digits have been set up and assuming that the A operator at the originating manual exchange has already plugged in, the sending of stepping impulses will commence under the control of the code switch CS. These impulses traverse a path from the stepping impulse sender SIS, back contact 90 and armature P¹, output control switch OCS, front contact and armature W¹, sender selector SS¹, armature G¹ and its front contact, trunk finder TF¹, front contact and armature F¹, to selectors such as D and E. The 95 translation of the digits originally stored on the first three storage relay groups is effected by suitable cross connections at the intermediate distributing frame IDF. When all 100 the exchange selecting digits, in this case 2, have been sent out, armature P¹ is operated and the code sender CIS comes into operation. This is then controlled from the storage relays SR so as to send out over the trunk line 105 code impulses which are received at a call indicator exchange and decoded, and by suitable means displayed to the operator. 110

When the sending of impulses is finished, the impulse sender is released and may be again taken into use for a further call, while the release of the armature F¹ completes the speaking connection. As will appear subsequently, the outlet finder OF is moved on one step as soon as the sending of impulses commences, and the operator may then at 115 once commence setting up another connection over an idle impulse sender seized for instance by the sender selector SS² associated with the second outlet. 120

The general principles underlying the invention having been explained, a more detailed description of the sequence of operation during the setting up of a connection will now be given with reference to Figs. 2-6. 125

The tandem operator is informed of the re- 130

quired number, over an order wire which is not shown, and she thereupon assigns an idle junction line, for instance, that comprising conductors 1 and 2. At the same time that 5 she gives the number of this line to the A operator in the manual exchange, she presses the assignment key 3, whereby the following circuit is completed for the assignment relay 4: earth, armature 16 and its back contact, operating 10 springs of assignment key 3, armature 52 and its back contact, normally closed springs controlled by armature 7, winding of relay 4 to battery. Relay 4, upon operating at armature 5 prepares a circuit for the trunk 15 busy lamp 65, at armature 6 removes earth from test contact 66 in the bank of the trunk finder, and prepares a circuit for relay 10, at armature 7 completes a locking circuit for itself so that the operator need not keep the 20 assignment key pressed, at armature 8 opens a point in the circuit of relay 37, and at armature 9 completes a starting circuit which extends as follows: earth, front contact and armature 9, lead 19, wiper 105 of the outlet 25 finder, lead 20, winding of relay 21 to battery. Relay 21 thereupon operates, at armature 23 connects switching relay 25 to earth at armature 29 in series with rotary magnet 26, and at armature 22 connects test wiper 68 to the 30 junction of relay 25 and magnet 26. Relay 21 also at armature 24 opens a point in the circuit of relay 30. The trunk finder is thus started up and commences to hunt for the contact 66 from which the earth has been removed by the operation of the corresponding 35 assignment relay 4.

A circuit is also completed from armature 9 over wiper 105, back contact and armature 122, winding of relay 107 to battery. Relay 40 107 at its armature 108 lights the outlet guard lamp 130 and prepares a locking circuit over the normally closed springs 137 of the outlet disconnect key for relay 25, at armature 109 prepares a circuit from earth at armature 150 for relay 111, and at armature 45 110 connects rotary magnet 126 to wiper 127 in the bank of the sender selector so that if this wiper is on an earthed contact the switch commences to hunt for an idle impulse sender. When 50 this is found, relay 111 is no longer short circuited and operates, thereupon at its armature 112 completing a circuit for relay 117, and at its armature 113 completing an alternative circuit for relay 25 so that this 55 shall not be deenergized when relay 107 releases. Moreover at its armature 114 it shunts armature 109 so as to complete a locking circuit for itself, at armature 115 opens the circuit of rotary magnet 126 and places 60 earth on test wiper 127, and at armature 116 opens a point in the circuit through the lower winding of relay 128. When earth is connected to lead 135 over wiper 127, the holding relay 253 is energized and at its armatures 65 258, 259 and 260 opens points in the circuit of

relay 246. Furthermore at armatures 255 and 254 it opens the restoring circuits of the input and output control switches respectively, at armature 256 prepares a circuit for relay 264, at armature 261 closes a point in a chain 70 busying circuit and at armature 262 prepares a supervisory circuit.

When the trunk finder has found the trunk which has been marked, relay 25 is operated, whereupon at armature 27 it opens the circuit 75 of the rotary magnet 26 and when an idle sender has also been seized connects earth from armature 115 to contact 66. At armature 28 it also completes a locking circuit for itself and at armature 29 prepares a circuit 80 for relay 30. The effect of the connection of earth to contact 66 is to complete a circuit which extends from contact 66, armature 6 and its front contact, back contact and armature 40, normally closed springs 69 of the 85 busy and cancel key, winding of relay 10 to battery. Relay 10 upon operating, at armatures 11 and 18 connects the outgoing trunk conductors 34 and 35 by way of contacts 71 and 72, wipers 73 and 74 to leads 75 and 76, 90 at armature 12 completes a circuit for the trunk lamp 65 which thereupon flickers under the control of the flicker drum 77, at armature 13 removes earth from back contact of armature 6 so that this shall not be connected to 95 contact 66 when relay 4 deenergizes, at armature 14 completes a locking circuit for itself, at armature 15 opens the circuit for relay 4, at armature 16 opens another point in the circuit of relay 4 and completes a circuit for 100 the upper winding of busy relay 59, and at armature 17 prepares a circuit for relay 37. When relay 21 deenergizes on the removal of earth from lead 19 armature 24 engages its back contact and a circuit is completed for 105 the upper winding of relay 30. This relay then operates its light armature 31 whereby earth is connected to the lower winding which is thus short circuited. The purpose of this relay is to initiate the sending of impulses 110 if this has not started when the operator presses a new assignment key as will be fully explained subsequently.

Relay 117 of the outlet relay group operates when its circuit is completed, at its armatures 118, 119, 120 and 121 connects the leads from the banks of the outlet finder through to the sender selector, at its armature 122 opens the circuit of relay 107 whereupon this relay deenergizes, at armature 123 prepares the circuit of relay 151, at armature 124 prepares the circuit of relay 157 and at armature 125 completes another circuit for causing the trunk lamp 65 to flicker. Thus relays 111 and 117 of the outlet relay group, relay 25 of the trunk finder and relays 10 and 59 in the trunk relay group are now operated. This is on the assumption, which has been made in order to simplify the description, that the A operator has not yet plugged in. The opera- 130

tion of relay 59 is without function at this stage since armature 16 is operated. The operator may now proceed to set up the required number on her digit keys.

5 For the sake of example suppose in the first instance that the wanted party is an automatic subscriber and that his number is 9013456; of this the first three digits 901 will be used for exchange selecting purposes, and 10 it will be assumed that they are converted into the digits 40. When the digit key 9 is pressed, a circuit is completed from earth, operated spring of digit key 9, lead 163, wiper 103, front contact and armature 120, 15 back contact and armature 148, wiper 143, lead 133, armature 209 and its back contact, wiper 203, lead 214, lower winding of relay 301, lead 302, back contact and armature 215, winding of relay 216 to battery. Relays 301 and 216 20 energize in series in this circuit, and the former at its upper armature locks itself up over its upper winding to lead 303 which extends by way of armature 217 and its back contact, normally closed spring 218 of the sender 25 disconnect key to lead 135 and thence over wiper 127, back contact and armature 158 to earth on the front contact of armature 115. Relay 216 upon operating, at armature 219 completes a circuit for rotary magnet 221 of 30 the input control switch which is arranged to step on release, and at armature 220 completes a circuit for slow relay 222 which thereupon operates its armatures 223 and 224 for a purpose which will be described subsequently. 35 A circuit is also completed from the operated springs of digit key 9 over lead 164 for relay 165, which energizes and at its armature 166 completes the following circuit: earth, front contact and armature 166, wiper 104, front contact and armature 121, back 40 contact and armature 152, lead 85, armature 33 and its back contact, lead 86, wiper 144, lead 134, armature 225 and its back contact, armature 210 and its back contact, armature 226 and its back contact, wiper 204, lead 227, lower winding of relay 305 to lead 302 and thence through the winding of relay 216 as before. Relay 305 energizes and locks up to lead 303 as did relay 301 and 50 also operates its lower armatures. When the operator releases the digit key 9, relay 216 is deenergized and opens the circuit of magnet 221 so that the wipers of the input control switch are moved on one step in readiness 55 for recording the second digit.

The operator will now press the digit key 0, whereupon at one of the operated springs of this key, a circuit will be complete over lead 163, which will be similar to that just 60 described except that it will now extend over wiper 204 in its second position to the third relay 306 in the second storage group. The operation of the digit key 0 also completes a circuit over lead 162, wiper 102, front contact and armature 119, back contact and

armature 147, wiper 142, lead 132, armature 208 and its back contact, wiper 202 and from the second contact in its bank to relay 307. Relays 306 and 307 energize in series with 70 relay 216 as previously described and lock themselves up to lead 303. Relay 216 remains energized until the key is released, whereupon the wipers of the input control switch are advanced into their third position.

75 The next digit on the assumption made is 1 and when the corresponding digit key is pressed a circuit is completed from earth, operated springs of key 1, lead 161, wiper 101, armature 118 and its front contact, so wiper 141, lead 131, armature 207 and its back contact, wiper 201 and over lead 228 to relay 308, which is the first one in the third storage group. When key 1 is released the input control switch is moved on one step 85 as previously described into its fourth position.

A circuit is now completed for relay 232 as follows: earth wiper 206, fourth contact 90 229 in its bank, normally closed springs controlled by armature 233, winding of relay 232 to battery. Relay 232 thereupon operates, at armature 233 completes a locking circuit for itself to the holding earth on armature 115, at armature 234 prepares a circuit 95 for relay 238, at armature 237 prepares a circuit over lead 253 for relay 404 and at armatures 235 and 236 completes a circuit over lead 241, armature 401 and its back contact, armature 410 and its back contact, lead 100 369, back contact and armature 320, winding of rotary magnet 315 to battery, and in parallel thereto through the rotary magnets of the other code switches, if there are more than one. These switches are thus set in operation and continue to hunt till wipers 333, 334 and 335 engage the contacts 329, 330 and 331 connected to leads 326, 327 and 328 respectively which have been marked by the 105 operation of the first three sets of storage 110 relays in response to the dialling of the digits 901. Relay 316 is of the shunt field type and only operates its armatures when it is energized by current through both its windings 115 in the proper direction; in the case shown, this condition is only fulfilled when wiper 334 finds battery and wipers 333 and 335 at the same time find earth. There is thus no 120 danger of relay 316 being energized when the associated wipers engage contacts which have been marked in response to some other 125 code very similar to the one in question, for instance having two digits the same. In the present case since relays 301 and 305 are operated, earth is connected to contact 329 over armature 322 and its back contact, armature 323 and its back contact, armature 324 and its front contact, and armature 325 and its front contact. While the code 130 switches are hunting the operator will set

up the remaining digits 3456, whereupon relays 309 and 310 in the fourth storage group, 311 in the fifth, 312 in the sixth, and 313 and 314 in the seventh storage group are energized, and lock up to the holding earth in the manner previously described. When the proper code switch i. e., the one shown, comes to rest having found the marked contacts, shunt field relay 316 is operated and at its 10 armatures 317, 318 and 319 connects up its wipers 336, 337 and 338 to the controlling leads 339, 340 and 341, respectively, at armature 320 opens the circuit of rotary magnet 315, and at armature 321 completes a 15 circuit for relay 400. Relay 400 upon energizing, at its armature 401 opens the circuit of all the rotary magnets, at its armature 403 prepares a circuit for the stepping impulse sender and at its armature 402 opens 20 the circuit of relay 404, the use and purpose of which will be described later.

After the setting up of the seventh and last digit, the input control switch will be stepped on in the usual manner, so that it will be 25 moved to its eighth position. Under these circumstances, while relay 222 holds up, a circuit is completed as follows: earth, wiper 206, contact 344, armature 223, and its back contact, back contact and armature 225, lead 334, wiper 144, lead 86, back contact and armature 33, lead 85, armature 152 and its back contact, armature 121 and its front contact, wiper 104, armature 166 and its back contact, winding of relay 167 to battery. Relay 167 30 upon operating, at its armature 168 completes a circuit which may extend to a totalling meter for registering the total number of calls dealt with by the position, at armature 169 completes a circuit for rotary magnet 160, 35 whereupon the wipers of the outlet finder are moved on one step and at armature 173 completes a circuit which extends over front contact and armature 123, winding of relay 151 to battery. At armatures 170, 171, and 172 40 similar circuits are prepared for relays similar to 151 associated with the other outlets, but as only one outlet at a time will be in a condition to have a starting circuit completed, the operation of these armatures is in this case 45 without effect. Relay 151 upon operating at armature 153 connects lead 79 directly to test wiper 127, at armature 154 prepares a circuit for relay 145, at armature 155 completes a locking circuit for itself, at armature 156 50 opens a point in the circuit of relay 157, and at armature 174 opens a point in the circuit for causing the trunk lamp to flicker.

The further operation is now dependent upon whether the A operator at the originating 55 manual exchange has plugged into the trunk assigned to her; in the normal course this will already have happened so that the sending of impulses will now at once commence. If she has not done so, impulse sending will be held up until she does; thereupon

battery is connected to the lower trunk conductor 2 at the distant end and a circuit then extends over conductor 2, normally closed springs 80, winding of relay 53, normally closed springs 67 of the busy or cancel key to 70 earth. Relay 53 thereupon operates, at its armatures 54 and 55 alters the circuit of the trunk busy lamp 65, at armature 56 prepares a circuit for the lower winding of relay 59 and at armature 57 completes a circuit for the 75 polarizing winding of relay 50 and also a circuit for relay 37 which extends over armature 17 and its front contact, back contact and armature 8, winding of relay 37 to battery. Upon the operation of relay 37, at armature 80 38 earth is fed forward over the release trunk conductor 36 to the succeeding selector. At armature 39 a circuit is completed for causing the trunk busy lamp 65 to glow continuously, at armature 40 the initial energizing circuit 85 of relay 10 is opened and at armature 41 the circuit over the upper winding of relay 59 is opened. Relay 37 furthermore at armature 42 completes a locking circuit for itself, at armature 43 prepares a circuit for the outlet 90 cancel relay 62, at armature 44 completes a circuit for starting the sending of impulses and at armature 45 connects relay 46 and the upper winding of relay 50 across the outgoing trunk line so as to prepare the supervisory 95 circuit.

The circuit completed by the operation of armature 44 extends over contact 87, wiper 88, lead 84, normally closed springs 138 of the outlet disconnect key, armature 154 and its 100 front contact, winding of relay 145 to battery. Relay 145 upon energizing, at armature 150 opens the circuit of relay 111 and at armature 149 connects the earth on lead 84 by way of wiper 146, lead 136, armature 105 247 and its back contact to relay 213 which thereupon operates. At armatures 207, 208, 209 and 210 the circuits to the wipers 201, 202, 203 and 204 are opened and at the front contacts of armatures 208 and 209, the impulsing 110 leads 249 and 250 are connected through to leads 132 and 133. At armature 211 earth is connected to lead 135 to replace that removed at armature 115 when relay 111 deenergizes, but as relay 111 is made slow to release there is no discontinuity in this operation. Relay 213 furthermore at armature 212 completes a circuit for relay 230 which by operating its armature 215 opens the energizing circuit of the storage relays, while at armature 252 a circuit is completed from earth at the front contact of armature 403, armature 407 and its back contact, interrupter springs 420, which are driven so as to be opened about ten times per second, lead 270, armature 252 120 and its front contact, lead 271, back contact and armature 445, winding of rotary magnet 431 to battery.

Upon the first completion of this circuit when springs 420 close magnet 431 is ener- 125 130

gized and operates its interrupter springs 436 and 437 neither of which however perform any useful function in this instance. When springs 420 next open, magnet 431 releases 5 and advances wipers 432 and 433 one step. A circuit is now completed from the earthed second contact in the bank of wiper 433 for relay 439 which operates and at its armature 440 prepares a locking circuit for relay 441 10 and at armature 438 removes a shunt from across the impulsing leads 249 and 250 leaving them under the sole control of armature 437. When therefore magnet 431 next energizes, an interruption is produced in the loop 15 across the outgoing trunk leads which extends as follows: lead 34, working contact and armature 11, contact 71, wiper 73, lead 75, front contact and armature 147, wiper 142, lead 132, armature 208 and its front contact, 20 lead 249, normally closed springs controlled by armature 467, armature 437 and its back contact, normally closed springs controlled by armature 468, lead 250, front contact and armature 209, lead 133, wiper 143, armature 148, 25 and its front contact, lead 76, wiper 74, contact 72, armature 18 and its front contact to lead 35. Upon the next opening of springs 420, magnet 431 deenergizes and advances wipers 432 and 433 another step. This operation continues until the wiper 432 encounters a contact to which earth is connected. As mentioned above, it will be assumed that in the present case the code 901 set up by the calling operator is converted into the 30 code 40 by suitable cross connections at the intermediate distributing frame (hereafter referred to as the I. D. F.). In consequence, earth is connected to the sixth contact in the bank of wiper 432 over the following circuit: 35 earth, wiper 451 of the output control switch, and the first contact in its bank, armature 413 and its back contact, lead 341, armature 319 and its front contact, wiper 338, contact 344, terminal 345 on the left hand side of the 40 I. D. F., jumper to terminal 346 on the right hand side of the I. D. F., lead 370 to contact 447; hence when the wiper 432 arrives on this contact 447, a circuit is completed for relay 441. At armature 442 it completes a locking 45 circuit for itself, at armature 443 completes a circuit for automatically advancing the wipers 432 and 433 to their normal position, at armature 444 completes a circuit for the magnet 448 of the output control switch, at armature 445 opens the circuit from the impulse springs 420 and at armature 445 shunts the interrupter springs 437 so that the subsequent operations of magnet 431 are ineffective to send impulses over the outgoing trunk line. 50 It will be appreciated that four impulses will have been sent to the distant selector when springs 437 are thus shunted wipers 432 and 433 are now automatically stepped on under the control of interrupter contact 436 until

wiper 423 reaches the dead contact 449 whereupon the circuit of relay 439 is opened and it deenergizes slowly, thereupon at its armature 440 opening the circuit of relay 441 which also deenergizes slowly. When armature 444 leaves its front contact, the circuit of magnet 448 is opened and it operates to advance the wipers 451, 452, 453 and 454 one step into engagement with the second contacts in their banks. Earth is now connected over wiper 451, armature 411 and its back contact, lead 340, armature 318 and its front contact, wiper 337, contact 343, terminal 347 on the left hand side of the I. D. F. terminal 348 on the right hand side of the I. D. F., lead 350 to contact 450. When the circuit of the rotary magnet 431 is again completed by the engagement of armature 445 and its back contact, wipers 432 and 433 are again stepped around in the manner previously described, and after they have moved one step relay 439 is energized, and, by operating armature 438, places the outgoing trunk conductors under the sole control of armature 437. It will be apparent in this case that ten impulses will be sent out before wiper 432 engages with contact 450. When this occurs relay 441 will be energized as before and wipers 432 and 433 will be automatically returned to their home position whereupon the circuit of relay 439 will be opened. 95

As in this instance it is being assumed that the call is going to another automatic exchange, the second sender for sending the code impulses will not in this case be required and the numerical digits will be sent out by the stepping impulse sender, which must thus continue to operate. When relay 441 deenergizes again, the circuit of magnet 448 is opened and wipers 451, 452, 453, 454, of the output control switch are moved on a further step. Since, however, it is desired to convert the code 901 comprising three digits into the code 40 comprising only two, it is now necessary that the output control switch should be stepped on past position 3 corresponding to a third exchange selecting digit. This is effected over wiper 336 of the code switch, since a circuit may be traced from earth, wiper 451, third contact in its bank, armature 411 and its back contact, lead 339, 100 armature 317 and its front contact, wiper 336, contact 342, cross connection to terminal 351 on the right hand side of the I. D. F., lead 352 to the third contact in the bank of wiper 453, so that the rotary magnet 448 receives an impulse and the wipers of the output control switch are moved into the position 4. In this case contact 456 in the bank of wiper 453 are all connected to earth as shown, consequently the output control switch will be stepped on to its position 8. These extra contacts are provided to permit the sending of more than three code digits 105 110 115 120 125

should it be necessary as fully described in the application Serial No. 723,124, previously referred to.

The output control switch is now in condition to control the sending of the numerical digits, which takes place in a manner very similar to that which has been already described for the code digits except that obviously in this case the contact marked in the 10 bank of wiper 432 corresponds to the number set up by the tandem operator. Thus the operation of relays 309 and 310 will have the effect of connecting earth to lead 353 which is connected to the contact in the bank 15 of wiper 432 corresponding to a train of three impulses. When these three impulses have been sent relay 441 is energized, the transmission of impulses ceases and the impulse control switch is stepped on into its home position 20 whereupon relays 439 and 441 deenergize. The output control switch is then moved on so as to control the sending of the next digit which it has been assumed is 4 and accordingly the contact corresponding to a 25 train of four impulses is marked in the bank of wiper 432 by the operation of relay 311. When this has been completed, the remaining digits 5 and 6 are sent in a similar manner and when relay 441 deenergizes after the 30 sending of the last digit the wipers of the output control switch are moved on into their eleventh position.

In this position a circuit is completed from earth on the eleventh contact in the bank of 35 wiper 454 and said wiper, lead 455, lower winding of relay 246 to battery. Relay 246 thereupon operates, at its armature 248 closes another point in the busy chain circuit so that the circuit is not opened when armature 261 40 falls away, at armature 247 opens the circuit of relay 213, at armature 217 removes earth from lead 135 and at armature 225 opens the circuit over lead 134 so as to prevent any further earth connections to this lead. Relay 213 is deenergized upon the operation of 45 armature 247 and at armature 211 removes earth from lead 303 so that all the operated storage relays are released and also relay 253, while at armature 212 relay 213 opens 50 the circuit of relay 230. The release of the storage relays opens the circuit of the operated shunt field relay which accordingly deenergizes and opens the circuit of relay 400 which also deenergizes. The opening of contact 55 252 on the deenergization of relay 230 prevents the impulse control switch from operating further, but in case it should be off normal at this time it is returned to its normal position over a circuit including armature 251 and its back contact. The code switches remain in the position last used, so that no circuit is necessary for returning them to normal. The deenergization of relay 253 completes a circuit at armature 255 for 60 magnet 221 including its interrupter contact 65

so that the input control switch is automatically moved on into one of its normal positions, of which three may conveniently be provided as shown if the switch is an ordinary 25 point rotary line switch. At armature 254 a circuit is completed over the multiplied contacts in the bank of wiper 452 and said wiper for magnet 448 so that the output control switch is restored to normal. Over armatures 258, 259 and 260 additional circuits are completed for relay 246 so as to maintain this relay operated until all the switches have been returned to their normal positions; this obviates the possibility of the impulse sender being taken into use for another call before it is ready. The removal of earth from lead 135 results in the deenergization of relay 151 which by releasing its armature 154 effects the deenergization of relay 145. Furthermore the removal of earth from lead 135 and hence from lead 83 opens the locking circuit of relay 10 which accordingly deenergizes and at the normally closed springs controlled by armatures 11 and 18 connects the outgoing trunk conductors 34 and 35 through. At armature 16 earth is momentarily connected to conductor 1 to inform the A operator that sending has ceased and at armature 13 earth is replaced on the contact 66 so as to guard the trunk line 95 against being taken into use by another finder. When relay 151 deenergizes, armature 153 leaves its front contact and earth is thereupon removed from lead 79, in consequence of which switching relay 25 in the trunk 100 finder is deenergized and the trunk finder is thus restored to normal since its wipers remain on the contacts last used. It will be noted that earth is only removed momentarily from lead 135, being replaced at the front 105 contact of armature 217 when relay 253 deenergizes, so that the impulse sender is guarded against seizure until relay 246 releases. All the apparatus connected with the particular outlet and impulse sender used has now 110 been released and the impulse sender may be seized by another operator. When relay 10 deenergizes, a circuit is completed over the loop for relays 46 and 50 only the former of 115 which however now operates.

Since it has been assumed that the call has gone over automatic switches to the wanted subscriber, he will be rung in the usual manner by the operation of the connector and when he replies the current flow over the 120 speaking leads 34 and 35 will be reversed. This current will then be in a direction to operate relay 50, which at its armature 51 connects the retardation coil 58 to conductor 1, thereby giving the calling operator answering supervision and at its armature 52 opens a point in the circuit of the assignment relay 4, so that no damage will be done should the operator press the assignment key 3 by mistake while the connection remains set up. 125 130

Upon the termination of the conversation when the called party hangs up relay 50 will again deenergize and by disconnecting the retardation coil 58 will notify the calling operator that she may take down the connection. When she removes the plug, relay 53 will deenergize, thereby opening the circuit of relay 37, which at armature 39 extinguishes the trunk busy lamp 65. All the apparatus associated with the particular trunk line is thus restored to normal and the trunk line may be used for setting up a further connection.

The case will now be considered in which a call instead of being extended entirely over automatic switches to the wanted party is made to a call indicator exchange, in which event after the exchange selecting operation effected in response to the first three digits set up by the tandem operator, the numerical digits of the wanted party's number are sent over the trunk line to the manual exchange in code. The code employed in this instance is that described in copending application of Ostline, Ser. No. 747,373, filed Nov. 1, 1924 and the apparatus for responding to it may be of the type there shown.

In order to explain clearly the functions of the various pieces of apparatus, it will be assumed that the manual exchange is represented by the code 475 as set up by the tandem operator and that this is then converted by means of the code switches into the two digit code 85. The subscriber's number may for convenience be assumed to be 3456 as before and in this case this number is sent out by means of code impulses as about to be described. It will further be assumed that the manual exchange is comparatively near so that the trunk line from the tandem exchange to it will be short. Under these circumstances it is desirable to insert certain resistances in the circuit over which the code impulses are sent in order to bring the total resistances of the circuit approximately up to that of the longest trunk line to a call indicator exchange which may be reached from the tandem exchange; thus a standard adjustment may be employed for the responding relays which is equally suitable for calls from all exchanges.

The effect of the setting up of the number 4753456 will be readily understood from the preceding description and need not be considered in detail. Suppose that the contacts marked in accordance with the exchange code are the contacts 354, 355 and 356. Then when the code switch comes to rest, contacts 357, 358, and 359 will be connected up over the wipers 336, 337 and 338, and contact 359 will control the sending of eight stepping impulses and contact 358 the sending of five. When however, the output control switch is moved to its third position, a circuit is completed over contact 357, terminal 360 and terminal

361 on the I.D.F., lead 362, upper winding of relay 459, upper winding of relay 456 to battery. Relays 456 and 459 both operate in this circuit and at their armatures 458 and 461 remove the shunts around the resistances 462 and 463, respectively, and at their armatures 457 and 460 complete a circuit which extends over back contact and armature 465, upper winding of relay 470 to battery. Relay 470 thereupon operates, at its armatures 471 and 472 prepares a locking circuit for its lower winding over the outgoing trunk leads, at armature 473 completes a circuit for relay 464 and at armature 474 opens the starting circuit for the code sending switch. Relay 464 at once energizes, at armature 465 opens the initial energizing circuit of relay 470, at armature 466 completes a locking circuit for itself to earth on lead 254 and at armatures 467 and 468 disconnects the leads from the stepping impulse control switch and connects the impulsing leads 249 and 250 through to the wipers 475 and 476. Relay 470 is now held up over the trunk line as described in the application of Ostline, Serial No. 747, 373, filed Nov. 1, 1924, until the operator at the distant manual exchange is ready to deal with the call, whereupon the loop is broken and relay 470 deenergizes.

A circuit is thereupon completed from earth on lead 254, armature 479 and its back contact, front contact and armature 469, armature 474 and its back contact, first contact in the bank of wiper 477 and said wiper, armature 482 and its back contact, winding of driving magnet 483 to battery. At this point it may be desirable to explain the inter-operation of relay 481 and driving magnet 483. It will be seen from the drawings that relay 481 is normally short-circuited by interrupter contact 484 and that the circuit of the driving magnet 483 is completed over armature 482 and its back contact, the sequence of operations being that when the magnet is energized it opens the contact 484, thereby permitting relay 481 to energize so that armature 482 leaves its back contact. The circuit of the driving magnet being thus opened it releases and again closes the interrupter contact 484. The particular advantage of this arrangement is that in a case such as the present where the speed of rotation is of importance the armature 482 may be adjusted so that the rate of generation of impulses is as high as is consistent with the reliable operation of the responding apparatus at the call indicator exchange; then in course of time, when wear of the contacts has taken place, the tendency will be for impulses to be generated at a slower rate and in no case at a quicker rate. There is thus no danger that after the lapse of time the speed of generation of impulses will be increased so that the call indicator equipment does not operate properly. An

advantageous arrangement is to have a micrometer adjustment on armature 482 as indicated by means of which the required speed of generation may be determined within 5 very fine limits. When a certain amount of wear has taken place and the speed of generation has become appreciably slower, it is a comparatively simple matter by means of the micrometer adjustment to increase it 10 again to the safe maximum.

By means of the multiplied contacts in the bank of wiper 477, wipers 475, 476, and 477 are, when once started, advanced automatically step-by-step over their respective contacts until they reach normal position again.

When they reach the third set of contacts a circuit is completed as follows: earth, contact 485, wiper 475, resistance 463, resistance 462, armature 467 and its front contact, lead 249, front contact and armature 208, lead 132, wiper 142, armature 147 and its front contact, lead 75, wiper 73, contact 71, armature 11 and its front contact, outgoing trunk conductor 34, over the responding apparatus in the call indicator exchange, trunk conductor 35, front contact and armature 18, contact 72, wiper 74, conductor 76, front contact and armature 148, wiper 143, lead 133, armature 209 and its front contact, lead 250, front contact and armature 468, wiper 476, contact 486, lead 487, front contact and armature 363, high resistance 364 to battery; this constitutes what may be termed a light positive impulse. When wipers 475, 476 and 477 come into engagement with the next set of contacts, a circuit is completed from earth in the bank of wiper 476 and said wiper, over the previously described circuit in the reverse direction, to wiper 475, contact 488, lead 489, armature 365 and its front contact, back contact and armature 366, low resistance 367 to battery. Since the low resistance 367 has been inserted in this circuit rather than the high resistance 364, this will be a heavy impulse and as the 45 current is in the reverse direction to that taking place previously, it is a negative impulse. In the next position of the code sending switch no circuit is completed since owing to the operation of relay 310 in the fourth storage group, armature 368 has left its back contact. In the following position of the switch current flows in a circuit which is identical with that last described except that it includes the high resistance 364 instead of the low resistance 367 so that a light negative impulse is sent.

As soon as the four positions corresponding to the first numerical digit have been passed over, the transmission of the second digit commences forthwith. The contacts controlling the code sending switch on the fifth storage relay group have not been shown, but are exactly similar to those shown on the fourth and seventh groups and the sequence 60 of operations will be followed without diffi-

culty. It may be said that in the first position of the switch no impulse at all is sent, in the second position a light negative impulse, in the third position a positive impulse and in the fourth position a further light negative impulse. Similarly the third and fourth numerical digits are sent, the third digit consisting of two light negative impulses and the fourth digit consisting of a positive impulse, a light negative impulse and a heavy negative impulse. When all the digits have been transmitted, the number is decoded and displayed to the manual operator who will complete the connection in any suitable manner.

As the code sending switch continues to move forward, when wiper 477 engages its 19th contact, the rotary magnet 483 is energized in series with the relay 478 which is of such low resistance as to permit the magnet 70 to operate. Relay 478 also energizes and at its armature 479 opens the initial energizing circuit for starting up the code sending switch so that this will be brought to rest when it reaches its first contact, and at armature 480 completes a circuit over lead 455 for relay 246 which operates with the results previously described. All the apparatus in the 80 sender is then released as described in the previous case, and the operations in the trunk 85 relay group are similar, suitable arrangements being provided at the call indicator exchange for instance for current reversal so as to give supervision to the operator at the originating manual exchange.

It should be understood that in case the call indicator exchange were reached over a trunk line which had a greater resistance, the connection at the I. D. F. would be altered so that only one or possibly neither of the compensating relays 456 and 459 were operated; for this purpose terminal 360 would be cross connected to one of terminals 371, 372 or 373. The case in which terminal 373 was used 90 would clearly be where the resistance of the 95 trunk line above that of the trunk line considered in the first case was equal to the sum of resistances 462 and 463. In case the manual exchange were reached in response to the three digit code, it would be necessary to have 100 a special code relay for energizing relay 470 or alternatively an additional wiper might be provided on the code switches, though this would probably be undesirable. The mode 105 of operation of such a code relay and the necessary connections to the banks of the wipers of the output control switch are fully 110 shown in the application Serial No. 723,124, previously referred to. Obviously any of the cases provided for there can be dealt with on 115 similar lines in the present instance.

The arrangements for securing the automatic starting of the sending of impulses in case the operator does not set up the full 120 seven digits will now be considered. Suppose 125

for instance that she sets up only three digits such as may be required for reaching a complaint or information operator's position; in this case relay 238 comes into operation. The 5 interrupter 245 is driven at such a speed that it supplies an earthed impulse at intervals preferably once every four seconds. When relay 232 is operated after three digits have been set up, interrupter 245 is connected up 10 over armature 240 and is back contact, front contact and armature 234, back contact and armature 224, lower winding of relay 238 to battery. When earth comes on, relay 238 which is of the two step type operates its light 15 armature 239 whereby earth from lead 135 is connected to the other terminal of its upper winding. On the termination of the impulse, relay 238 energizes fully over both its windings in series and at armature 240 transfers 20 the connection from the interrupter to lead 134 by way of the back contact and armature 225. It will be noted that this circuit for relay 238 is not operative as long as relay 222 is energized owing to the operation of 25 armature 224. This will occur while the number is being set up and for a short time afterwards, and serves to prevent the initiation 30 of the sending of impulses while the operator is still setting up an ordinary seven digit number. It will be noted also that relay 238 operates armature 226 so that the connection of earth to the lead 134 shall not operate one of the storage relays in for instance the fourth group. The connection of 35 earth to lead 134 when interrupter 245 again closes its contacts operates the start relay 167 in the manner previously described and the sending of the stored digits takes place as before. A further means for automatically 40 starting the sending of impulses is provided in connection with the trunk finder. Suppose that the operator has set up a connection which does not comprise the full number of digits and that she then assigns another trunk line in order to deal with the 45 succeeding call before the arrangement described above comes into action. The effect of the pressing of the assignment key associated with the new trunk line will be to operate the line relay 21 of the same trunk 50 finder as is already in use, and this will accordingly operate its armatures, of which however, only the armature 24 is able to produce any effect. Relay 30 it will be remembered has operated its light armature 31 so 55 that earth is connected to both terminals of its lower winding. When armature 24 leaves its back contact, however, earth is removed from the middle point of the winding of relay 30 and this relay then operates 60 fully, thereby at armature 33 and its front contact connecting earth to lead 85 and hence over wiper 104 and armature 166 and its back contact to the start relay 167, so that the 65 starting of the sending takes place as before.

The operation of relay 167 completes a circuit for the rotary magnet 160 so that the outlet finder is moved on one step and another trunk finder is taken into use over which the call may be set up in the ordinary manner. 70

The case will now be considered in which owing to a mistake on the part of the tandem operator an exchange code is set up which does not correspond to any of those provided for. In this event if no arrangements were 75 made, the code switches would continue to hunt and if the operator remained unaware of her mistake, the call would be lost or mutilated. To guard against this, relays 405 and 408 are provided and the operation is as follows: The interrupter 242 in Fig. 4 is arranged to send an earth impulse at intervals of preferably two seconds; hence when relay 232 is energized on the input control switch arriving at its fourth position, a circuit is 80 prepared from earth over interrupter 242, front contact and armature 237, lead 253, armature 406 and its back contact, back contact and armature 402, upper winding of relay 404 to battery. This circuit it should be 85 understood is completed in any case in the normal working but when a code switch finds the marked contacts relay 400 is operated and at armature 402 the circuit of relay 404 is opened. In case a dead number has been set 90 up, however, upon the first impulse given by the interrupter 242, relay 404 will be partially energized over its upper winding and will operate its light armature 405 whereupon earth from lead 254 will be connected to the 95 other terminal of its lower winding. On the termination of the impulse, the lower winding will no longer be short-circuited and the relay will operate fully, thereupon at its armature 406 transferring the circuit over 100 lead 253 to the winding of relay 408. Consequently after another two seconds, when earth is again connected to lead 253, relay 105 408 is energized. At armature 414 it locks itself to lead 254, at armature 409 completes 110 a circuit for relay 400, at armature 410 opens the circuits for the rotary magnets of the code switches so that these are brought to rest and at armatures 411, 412, and 413 disconnects 115 the leads from the bank of wiper 451 from the leads 339, 340 and 341 and connects them through to special terminals 374, 375, and 376 on the I. D. F., which are suitably cross connected so as to route the call to a special operator's position. This special operator 120 then deals with the call and is able to inform the calling party as to why this call has failed. After the impulses have been sent out for routing the call to the operator, relay 246 125 is operated, for instance by a special earth connection to the eighth contact in the bank of wiper 454, and the impulse sender and the associated apparatus are released in the manner previously described.

The purpose of relay 264 may now be ex- 130

plained. The interrupter 257 is arranged to give an earth impulse conveniently once every eight seconds and when relay 253 operates on the seizure of the impulse sender, interrupter 257 is connected up over armature 266 and its back contact. Consequently when the interrupter 257 next gives an impulse relay 264 is partially energized by its lower winding and operates its light armature 265 5 and on the termination of the impulses operates fully, thereupon at its armature 266 connecting the interrupter 257 to lead 455. After a further eight seconds therefore, in case the impulse sender is still in use, relay 264 will 10 be energized from interrupter 257 and will operate as usual to release all the apparatus. It is thus impossible for an impulse sender to remain locked up indefinitely owing to some defect. The time allowed, from eight 15 to sixteen seconds, is arranged to be amply sufficient for the complete operation of the impulse sender in the normal course.

In order that the operator may release the apparatus in case she finds she has set up 25 the wrong number, cancellation keys are provided. Two cases must be considered: firstly that in which the operator discovers her mistake before the actual sending of impulses commences and secondly, that in which sending has already commenced before she realizes her error. In the first case, she will press key 175 which is common to all the outlets, whereupon a circuit will be completed from earth, key 175, front contact and armature 30 124, back contact and armature 156, winding of relay 157 to battery. The operation of relay 157 causes armature 158 to leave its back contact, whereupon the earth at armature 115 is removed from the lead 135 so that 35 all the storage relays which have been operated are released as is also relay 253, whereupon the input control switch is returned to normal. It will be noticed however, that no alteration is made to the condition of the 40 trunk relays and consequently the operator may now proceed to set up the correct number and the connection will be completed in the usual manner. Should impulse sending 45 actually have commenced however, before the mistake is realized, it will be necessary for the operator to press the busy or cancel key which is associated with the trunk line taken into use. When she does this the holding 50 earth for the trunk relay is removed at spring 67 and the trunk lamp 65 is lighted. Furthermore at spring 69 the circuit of relay 55 10 is opened and at spring 70 a circuit is completed for the outlet cancel relay 62 which is common to all the trunks. This at its armature 63 completes a circuit over lead 78 whereby the outlet finder is moved forward into engagement with another outlet while at armature 64 the connection of the flicker drum 77 is broken. The deenergization of relay 65 60 removes earth at armature 44 from the con-

trol lead 84 and hence it is also removed from lead 136 so that relay 213 deenergizes. This accordingly removed the holding earth at armatures 211 and 212 and the impulse sender is released. It will now be necessary for 70 the operator to press the assignment key again and the call will then be set up over a fresh outlet and another impulse sender.

The operation of the busy relay 59 may now be considered; this is energized over its 75 upper winding from armature 16 after relay 10 operates until relay 37 operates. At its armature 60 it prepares a busying circuit, which is however, without effect at this time owing to the removal of earth from the back 80 contact of armature 16 but as explained above serves to give the manual operator a momentary signal when the sending of impulses is finished. Furthermore at armature 61 a circuit is prepared for the outlet cancel 85 relay 62. After the sending of impulses has commenced, in case either a group should be found busy, in which case the selector will be driven to the eleventh contact or in case the calling subscriber should be busy, busy 90 tone and busy flash battery will be connected alternately to the lower trunk conductor 35. Consequently when relay 10 deenergizes on the termination of impulse transmission relay 46 is only energized intermittently since 95 no circuit is completed for it when battery is connected to conductor 35. A circuit is completed each time relay 46 deenergizes for the lower winding of relay 59 over back contact and armature 49 and front contact and armature 56. Relay 59 therefore operates and at its armature 60 connects earth intermittently to the trunk conductor 1 so that the calling operator is notified by the flashing of the supervisory lamp. 100

The emergency order wire key on the extreme left of Fig. 1 is provided in order that the junction line from the manual exchange may in case of necessity be used as an order wire. When it is operated, at spring 82 a 110 circuit is completed for the trunk busying lamp 65 and at springs 80 and 81 leads 1 and 2 are disconnected from the trunk relay group and connected to leads 89 and 90 extending to the usual order wire keys. The lighting 115 of lamp 65 then indicates to the tandem operator that the trunk line is not available, and must not be assigned.

In case the trunk line is out of order, the busy or cancel key will be operated and this 120 will have the effect of lighting lamp 65 and placing the trunk relay group in such a condition that it cannot be operated. The outlet disconnect key is operated in case a particular outlet is out of order. This at spring 125 140 lights the outlet guard lamp 130 and at spring 139 connects earth to the contact associated with the outlet in the bank of wiper 106 so that this outlet cannot be taken into use. At springs 137 and 138 the connections 130

to leads 79 and 84 are broken so that the relays associated with the outlet are rendered inoperative. The sender disconnect key will be operated in case a particular sender is out of order whereupon at spring 218 the through circuit for locking up the storage relays is broken and earth is connected to lead 135 so as to prevent the sender being taken into use while at spring 229 a point is completed in the chain circuit, which will now be described.

Each sender has three contacts in parallel in this chain circuit, springs 229 of the sender disconnect key, contacts 248 of the relay 246 and contacts 261 of the relay 253. While the sender is in normal use, armature 261 will engage its front contact and during the release of the sender armature 248 will be operative; thus as long as the sender is not available for use its corresponding point in the chain circuit will be closed. When all the senders in a group (which in the example shown comprises 25) are in use a circuit will be completed over lead 159 and at armature 116 and its back contact for the lower winding of relay 128 which thereupon operates and at its armature 120 busies the outlet having access to this particular group. The outlet finder is thus stepped on into engagement with another outlet with which the idle senders are associated and no time is wasted with useless hunting. Relay 128 is also provided with an upper winding which is connected to the fuse alarm of the trunk finder associated with this outlet. Consequently if the trunk finder should be put out of action by the blowing of this fuse the outlet would be automatically busied and the operator would not be held up.

The operation of the various lamps provided will now be considered. The outlet guard lamp 130 is operated as long as an outlet is in use or in case the outlet disconnect key is operated. As has already been pointed out, the trunk lamp 65 will glow steadily in case either the emergency order wire key or the busy or cancel key is operated but in order to keep the operator informed of the progress of the connection, it is arranged that in addition to glowing steadily it may either flash or flicker. In order that this may be better understood, consider first that the tandem operator completes all her operations before the A operator plugs in. When the assignment key is pressed the lamp commences to flicker in the following circuit upon the operation of relay 117; earth, flicker drum 77 back contact and armature 64, common lead 87', back contact and armature 174, armature 125 and its front contact, common lead 88', armature 5 and its front contact, back contact and armature 54, back contact and armature 12, trunk lamp 65 to battery. When both the sender selector and the trunk finder have come to rest, relay 10 energizes and the circuit is then altered so that it now extends from the flicker drum 77, back

contact and armature 64, armature 55 and its back contact, front contact and armature 12 to lamp 65. This condition exists until the A operator plugs in, whereupon relay 37 is operated and at armature 39 a circuit is completed for causing the lamp to glow steadily. Since the relay 37 remains energized throughout the connection the lamp remains lighted also and when it is finally extinguished, the tandem operator knows that the trunk line is again idle and may be used for setting up another connection. In case the A operator plugs in before the B operator presses her assignment key, relay 53 will be operated and a circuit will now be completed from earth, so flashing interrupter 48, back contact and armature 47, front contact and armature 54, back contact and armature 12 to lamp 65. When the assignment key is pressed the lamp is extinguished by the operation of armature 12 and then lights and glows steadily owing to the operation of armature 39 by relay 37.

The purpose and method of operation of the supervisory arrangements for the senders will now be described. It will be noted that all the rotary magnets in the sender are connected to battery through the winding of relay 490 which is of very low resistance, probably only a fraction of an ohm. Consequently when any of these magnets are operated, relay 490 pulls up and at its armature 491 completes a circuit for the supervisory lamp 492 which circuit extends over the normally closed contacts controlled by armature 500, low resistance winding of relay 493 to earth. Lamp 492 therefore lights and relay 493 pulls up and at its armature 494 completes a circuit for operating the slow set or dash-pot relay 495. Under normal circumstances the magnets will be energized intermittently and for so short a time that the relay 495 will never be able to close its contact 496. In case however one of the switches should become stuck and current continue to flow through the corresponding magnet, contact 496 would be closed after a suitable interval and relay 497 would thereupon be energized. This at armatures 499 and 500 completes an alternative circuit for the supervisory lamp 492 and at its armature 501 connects up relay 502 to the interrupter 498. When relay 502 energizes under the control of the interrupter, as happens at intervals, the circuit of the supervisory lamp is transferred from the low resistance relay 493 to relay 503, the resistance of which is so high that the lamp does not light in series with it. Moreover at armature 504 an additional circuit is completed for the dash pot relay 495, so that this will maintain its armature attracted as long as the abnormal conditions persist. The flashing of the supervisory lamp 492 thus indicates to the attendant that there is trouble with one of the switches in a particular impulse sender and this can then be looked to. It should be remarked that the relay 490 and 130

the lamp 492 and of course, the contact 262 are individual to each sender, while the supervisory relays and the key 367 are common to a group of senders. The operation of the key 267 while lighting the corresponding lamps serves to show which senders are in use though these lamps would be already lighted if any of the magnets were energized.

What is claimed is:

1. In a telephone system, an operator's keyboard, register sets on which wanted subscribers' numbers are stored directly by said keyboard and sending devices of two different kinds both associated with and directly controlled by the register sets, means being provided whereby one sending device transmits all the impulses of one kind corresponding to an entire desired number or only transmits a portion of the required number and the other sending device in the latter instance subsequently transmits impulses of a different kind corresponding to another portion of the required number.

2. In a telephone system, a register set on which wanted subscribers' complete numbers are adapted to be initially set up and sending devices of two kinds directly controlled by said register set, that part of the register set which registers the exchange designation of the wanted subscriber being adapted to cause the operation of one sending device to control switches for selecting the required exchange and also to determine whether subsequently the first device will continue to operate or the second device be brought into operation to transmit impulses of a different kind in accordance with the setting of the other part of the register set which registers the numerical designation of the wanted subscriber.

3. An impulse sending device comprising register sets on which wanted subscribers' numbers are stored, sending devices of two kinds associated with the register sets, one for sending impulses to operate the switches which perform an exchange selection function, the other for sending impulses for operating call indicators at the exchange selected, and a translating device consisting of a hunting switch set in operation after the digits it is to translate have been registered to simultaneously test for and find all contacts which have been marked in response to the registering of said digits.

4. An impulse sending device as claimed in claim 3 in which if the hunting switch fails to find a set of marked contacts within a predetermined time, its operation is stopped and a special relay is operated to trunk the call to an operator.

5. In a telephone system, impulse sending and registering devices, means for retransmitting called telephone numbers registered on said register devices, means for automatically causing such retransmission to auto-

matically start after a group of numbers have been registered in all the said register devices, means automatically effective after an interval if only a part of a number has been registered, and other means at times effective to start the retransmission in the latter instance before the predetermined interval has elapsed.

6. In a telephone system, an operator's switchboard, trunks extending from the switchboard terminating in automatic switches having access to a plurality of exchanges, digit registering and sending equipment, an assignment key at the switchboard, means responsive to the actuation of said key for associating a trunk with said key set and with said digit registering and sending equipment, means responsive to the operation of various keys of the key set for causing the corresponding digits to be registered and subsequently retransmitted after an interval, said assignment key also effective upon its being again operated prior to the expiration of said interval, for causing the retransmission to start at once.

7. In a telephone system, A and B operators' switchboards, trunk lines extending to other exchanges, impulse registering and transmitting equipment at the B operator's switchboard, an assignment key, means controlled by the operation of said key for causing the registering and transmitting equipment to be associated with its associated trunk, a supervisory signal at the B switchboard, means for intermittently operating said signal until the trunk and sender are connected and for operating said signal steadily thereafter, a key set by means of which the operator at the B board may now cause the registration and transmission of the called number to take place, and means for automatically transmitting an impulse back to the A board responsive to the complete transmission of the called number.

8. In a telephone system, automatic switches, key board controlled impulse senders common to a number of operators, said impulse senders being adapted for use in setting up both, connections which are completed to a wanted party by means of said automatic switches and those which are completed by an operator at a call indicator position, circuit arrangements for starting the transmission of impulses for establishing the desired connection when the full number of digits have been set up and automatically initiated in case less than the full number are used when the operator commences to deal with the succeeding call.

9. In a telephone system, a register set on which wanted subscribers' numbers are adapted to be set up, sending devices of two kinds controlled by the register set, that part of the register set which registers the exchange designation of the wanted subscriber

being adapted to cause the operation of one sending device to control switches for selecting the required exchange and also to determine whether subsequently the first device 5 will continue to operate or the second device be brought into operation to transmit impulses of a different kind in accordance with the setting of the other part of the register set which registers the numerical designation 10 of the wanted subscriber, the said sending device for controlling the generation of impulses of the first kind, including a step by step switch which is cut out when a change is made from the transmission of impulses of 15 one kind to those of the other kind.

10. In a telephone system, register sets on which wanted subscribers' numbers are stored, sending devices of two kinds associated with the register sets, and a translating device consisting of a hunting switch set in operation after the digits it is to translate have been registered to find contacts which have been marked in response to the registering of said digits, said hunting 20 switch being provided with a plurality of wipers three of which are connected to a shunt field relay which on energization serves to bring the switch to rest while the remaining wipers in turn serve to control the generation of trains of impulses of the same kind but of different values.

11. In a telephone system, register sets on which wanted subscribers' numbers are registered, sending devices of two kinds associated with said register sets, one for sending impulses to operate the switches which perform an exchange selecting function, the others for sending impulses for operating call indicators at the exchange selected, a translating device consisting of a hunting switch set in operation after the digit it is to translate has been registered to find contacts which have been marked in response to the registration of said digits, and means for stopping said hunting switch and for trunking the call to an operator should the switch fail to find a set of contacts within a predetermined time.

12. In a telephone system, a register set on which wanted subscribers' numbers are adapted to be set up, sending devices of two kinds controlled by the said register set, that part of the register set which registers the exchange designation of the wanted subscriber being adapted to first adjust the circuit over which the impulses are to be sent so as to maintain the resistance of the circuits substantially constant irrespective of the resistance of the trunk line leading to the exchange selected and also to determine 55 whether subsequently the first device will continue to operate or the second device be brought into operation to transmit impulses of the different kind in accordance with the setting of the part of the register set which

registers the numerical designation of the 65 wanted subscriber.

13. In a telephone system, a register set on which wanted subscribers' numbers are adapted to be set up, sending devices of two kinds controlled by the said register set, said 70 registering set comprising a plurality of sets of relays, one set for each digit, certain of the sets of relays being provided with two distinct sets of contacts one contact set adapted to control the sending device of the first 75 kind and the other set adapted to control the sending devices of the other kind.

14. In a telephone system, in which connections are set up over automatic switches with the help of operators by means of key 80 board controlled impulse senders common to a large number of operators, and in which the same impulse senders are adapted to be used for setting up both connections which are completed to the wanted parties by means 85 of automatic switches and those which are completed by an operator at a call indicator position, means for causing the sending of impulses for establishing the desired connections to be initiated when the full number 90 of digits have been set up, and means for causing the sending of impulses to be automatically initiated when the operator commences to deal with the succeeding call when less than the full number has been set up.

15. In a telephone system in which connections are set up over automatic switches with the help of operators by means of key 95 board controlled impulse senders common to a large number of operators, and in which, 100 the same impulse senders are adapted to be used for setting up both connections which are completed to the wanted party by means of automatic switches and those which are completed by an operator at a call indicator 105 position, characterized in this, that means is provided whereby the sending of impulses for establishing the desired connection is automatically initiated after the lapse of a predetermined time.

16. In a telephone system, a relay register set on which wanted subscribers' numbers are stored, a first sending device associated with said relay register set and controlled thereby to send one kind of impulses which correspond to the digits of a wanted number to perform the exchange and station selection, and a second sending device also associated with and controlled by said relay register set to send impulses of a different kind in a 115 code suitable for operating call indicators at the exchange selected.

17. In a telephone system containing manual offices and automatic offices, automatic switches in the automatic offices responsive to 120 control of a given character, call indicators in the manual offices responsive to control of a different character, register senders in the

automatic offices having registering apparatus including a separate register set for each of certain digits in called numbers, each of said register sets having two separate contact sets, sending means in said register senders controlled through one of the contact sets in said register sets in accordance with the registered number to exercise the control necessary to set the automatic switches, and 10 other sending means in said register senders controlled through the other contact sets of said register sets in accordance with register numbers to exercise the control necessary to operate the call indicators.

15 18. In a register sender for use in a telephone system, a register set having two sets of contacts, two sending devices, means effective depending upon the class of a connection being handled by the register sender for operating one sending device or the other in accordance with the setting of said register set, one set of contacts on said register set for controlling one sender, and a separate set of contacts on said register set for controlling the other sender.

19. In a register sender for use in a telephone system, a register set, two senders either of which is arranged to send impulses in accordance with the setting of said register set, one of said senders being arranged to send impulses of one character, a set of contacts on said register set for controlling the said one sender in a sending operation, the other sender being arranged to send impulses of a different character, and a separate set of contacts on said register set for controlling said other sender in its sending operation.

20. In a register sender for use in a telephone system, a control conductor outgoing

from said register sender over which switch operating impulses may be transmitted to automatic switches, a register set in said register sender arranged to be set in accordance with digits in a telephone number, a sender within said register sender arranged to send the switch-operating impulses over said outgoing control conductor in accordance with the setting of said register set, and another sender within said register sender arranged to send over said outgoing control conductor impulses of a character different from the character of the switch operating impulses and in accordance with the setting of said register set.

21. In a register sender for use in a telephone system, a control conductor outgoing from said register sender, means for operating said register sender to transmit a portion of a telephone number by sending impulses of either of two characters over said outgoing conductor, and means for determining the character of impulses in accordance with the character of the switching apparatus through which a connection must be set up to the called line.

22. In a telephone system, automatic step-by-step switching apparatus, a manual switchboard having call indicating apparatus thereat, a register sender, and means for operating said register sender to store a desired number and to operate said step-by-step switching apparatus to extend a connection to said switchboard and to operate said register sender to set said call indicator apparatus.

In witness whereof, I hereunto subscribe my name at Liverpool, England, this 14th day of October, 1924.

WILLIAM OGLESBY PASSMORE.
